UNITED STATES PATENT OFFICE

EDWARD W. BURGESS, OF MILWAUKEE, WISCONSIN, ASSIGNOR TO A. O. SMITH CORPORATION, OF MILWAUKEE, WISCONSIN, A CORPORATION OF NEW YORK

METALLIC FLOOR GRID

Application filed July 31, 1931. Serial No. 554,276.

This invention relates broadly to metallic floor grids, such as disclosed in my former Patent No. 1,765,652 issued June 24, 1930, for embedding in a floor or pavement and to increase the wear resisting quality of the tread surface thereof.

More specifically the invention relates to means for securing adjacent grid sections together, and to a flooring or pavement composed of a plurality of grid sections secured together by such means.

In the drawing which illustrates a preferred embodiment of the invention:

Figure 1 illustrates diagrammatically the arrangement of a plurality of grid sections constituting a portion of a floor or pavement prior to the pouring of cement, concrete or other paving material around the grids, and also illustrates the arrangement of the clips for securing the grid sections together;

Fig. 2 is an enlarged detail view of portions of two grid sections showing the manner of securing the two together;

Fig. 3 is a sectional view taken on a plane indicated by the line 3-3 in Fig. 2; and

Fig. 4 is a perspective view of one of the clips.

In preparing a wear resisting grid for incorporation in a floor or pavement, a plurality of grid sections 10 are arranged in staggered relation as shown in Fig. 1 of the drawing and are secured together by means of clips 11.

Each of the grid sections 10 is made of a single piece of sheet metal in a manner such as described in the patent above referred to, and comprises a plurality of longitudinal rows of paving material receiving rings or cups 12 which are secured together and maintained in spaced relation by means of webs 13. Each of the cups is provided with a plurality of depending projections 14 for increasing the bond between the grid and the paving material. As shown in Fig. 2 of the drawing, the individual cups of alternate longitudinal rows are staggered, thereby providing rows of cups at diagonals to the longitudinal rows in each section.

The clip 11 for securing adjacent sections together comprises a channel shaped member

having a web 15 and side flanges 16. Struck down from web 15 are a plurality of aligned retaining tongues 17 which are spaced from the web 15 a distance substantially equal to the thickness of the connecting webs 13 of the grid sections. The outer free ends of the tongues are bent down slightly as at 18 to facilitate entry of the connecting webs 13 into the space between the web 15 and the tongues 17 when the clips are driven into retaining position. The width of the clips 11 is substantially equal to the width of the space between adjacent rows of cups and the flanges 16 are not as high as the cups.

In preparing grid sections, such as illustrated in Fig. 2, for incorporation in flooring or pavement, the grid sections are first arranged with the rows of cups of adjacent sections in substantial alignment. A clip 11 is then placed across the line of division of the two sections and between adjacent diagonal rows of cups of one section and corresponding rows of cups of the adjacent section with the tongues 17 of the clip disposed within the spaces between the connecting webs 13, and the web 15 of the clips resting upon the connecting webs 13. Since the width of the clip 11 is substantially equal to the space between adjacent rows of cups, the diagonal rows of cups of adjacent sections will be brought into proper alignment. The clip is then driven longitudinally to position the various connecting webs 13 between the tongues 17 and the web 15 of the clips. The diagonal rows of cups extending in one direction will not only be aligned, but the upper edges of the cups will be brought into substantially the same horizontal plane.

Another clip 11 is then disposed across the division line of the adjacent sections, but is so positioned as to extend in a diagonal line opposite to the diagonal line in which the first clip was positioned and it is then driven longitudinally in a manner similar to that described in connection with the first clip. By having the two clips disposed divergently with respect to each other, the last longitudinal row of one section is aligned with the first longitudinal row of the second section in addition to aligning the diagonal rows

of the two sections. The clips also act as a reenforcement for the floor or pavement to prevent cracking thereof along lines of division between adjacent grids.

5 The ends of the adjacent grid sections are secured together by means of clips 11 extending at right angles to the line of division of the sections. As shown in Fig. 1, it will be clear that any size paving grid may be built 10 up of a plurality of sections in a manner above described, and that the longitudinal and transverse or diagonal rows of cups will all be accurately aligned and the upper wear resisting edges of the cups will be brought 15 into substantially the same plane.

After the grid has been built up, the concrete, cement, terrazzo, or other paving or floor material is poured in and around the grid and leveled off substantially flush with 20 the tops of the cups. The depth of the clips being less than the depth of the cups, the latter will be covered over by the paving material leaving only the upper edges of the cups showing on the tread surface of the pave- 25 ment.

Although the clips 11 have been described in connection with the particular floor grid shown, it is to be understood that the clips can be used with any form of grid which has 30 equally spaced webs or similar parts with which the tongues 17 may cooperate and it is to be further understood that various modifications may be resorted to without departing from the scope or spirit of the invention.

35 What is claimed and desired to be secured by Letters Patent is:

1. A wear resisting grid for pavements composed of a plurality of grid sections, each having longitudinal and transverse rows of 40 material receiving cups and webs connecting the cups and maintaining the same in spaced relation, and clips extending across the lines of division of adjacent grid sections for securing the same together, said clips being disposed between adjacent rows of cups of one section and corresponding adjacent rows of 45 cups of an adjacent section for properly aligning and spacing the longitudinal and transverse rows of cups of the several sections.

55 2. A wear resisting grid for pavements composed of a plurality of grid sections, each having longitudinal and transverse rows of material receiving cups and webs connecting the cups and maintaining the same in spaced relation, and clips extending across the lines of division of adjacent grid sections for securing the same together, said clips each having a plurality of retaining tongues engaging 60 the connecting webs between cups and being disposed between adjacent rows of cups of one section and corresponding adjacent rows of cups of an adjacent section for properly aligning and spacing the longitudinal and transverse rows of cups of the several

sections and causing the upper wear resisting edges of the cups to lie in substantially the same plane.

3. A wear resisting grid for pavements composed of a plurality of grid sections, each 70 having longitudinal and transverse rows of material receiving cups and webs connecting the cups and maintaining the same in spaced relation, and clips extending across the lines of division of adjacent grid sections for securing the same together, said clips each having a plurality of retaining tongues engaging the connecting webs between cups, being of a width substantially equal to the width of the space between adjacent rows of cups and being disposed between adjacent rows of cups of one section and corresponding adjacent rows of 75 cups of an adjacent section for properly aligning and spacing the longitudinal and transverse rows of cups of the several sections and causing the upper wear resisting edges of the cups to lie in substantially the same plane.

4. A wear resisting grid for pavements composed of a plurality of grid sections, each 80 having longitudinal and transverse rows of material receiving cups and webs connecting the cups and maintaining the same in spaced relation, and clips extending across the lines of division of adjacent grid sections for securing the same together, said clips being disposed between adjacent transverse rows of 85 cups of adjacent grid sections for aligning the transverse rows of one section with the transverse rows of the adjacent section and properly spacing the last longitudinal row of cups of one section with the first longitudinal row of the adjacent section.

5. A wear resisting grid for pavements composed of a plurality of grid sections each 90 having longitudinal rows of material receiving cups and webs connecting the cups and maintaining the same in spaced relation, the cups of alternate rows being staggered to provide rows of cups in each section at a 95 diagonal with respect to the longitudinal rows of cups, and clips extending across the lines of division of adjacent grid sections for securing the same together, said clips being disposed between adjacent diagonal rows of 100 cups of adjacent grid sections for aligning diagonal rows of cups of one section with diagonal rows of cups of an adjacent section and properly spacing the last longitudinal row of cups of one section with the first longitudinal row of the adjacent section.

6. A wear resisting grid for pavements composed of a plurality of grid sections each 105 having longitudinal rows of material receiving cups and webs connecting the cups and maintaining the same in spaced relation, the cups of alternate rows being staggered to provide rows of cups in each section at a 110 diagonal with respect to the longitudinal rows of cups, and clips extending across the lines of 115 division of adjacent grid sections for securing the same together, said clips each having a plurality of retaining tongues engaging the connecting webs between cups, being of a width substantially equal to the width of the space between adjacent rows of cups and being disposed between adjacent rows of 120 cups of one section and corresponding adjacent rows of cups of an adjacent section for properly aligning and spacing the longitudinal and transverse rows of cups of the several sections.

division of adjacent grid sections for securing the same together, said clips being disposed between adjacent diagonal and longitudinal rows of cups of one section and corresponding rows of adjacent sections for aligning and properly spacing the rows of cups of the sections.

7. A wear resisting grid for pavements composed of a plurality of grid sections each having longitudinal rows of material receiving cups and webs connecting the cups and maintaining the same in spaced relation, the cups of alternate rows being staggered to provide rows of cups in each section at a diagonal with respect to the longitudinal rows of cups, and clips extending across the lines of division of adjacent grid sections for securing the same together, said clips each having a plurality of retaining tongues engaging the connecting webs between cups and being disposed between adjacent diagonal and longitudinal rows of cups of one section and corresponding adjacent rows of adjacent sections for aligning and properly spacing the longitudinal and diagonal rows of cups of the sections.

8. A wear resisting grid for pavements composed of a plurality of grid sections each having longitudinal rows of material receiving cups and webs connecting the cups and maintaining the same in spaced relation, the cups of alternate rows being staggered to provide rows of cups in each section at a diagonal with respect to the longitudinal rows of cups, and clips extending across the lines of division of adjacent grid sections for securing the same together, said clips each having a plurality of retaining tongues engaging the connecting webs between cups and being of a width substantially equal to the width of the space between adjacent rows of cups and being disposed between adjacent diagonal and longitudinal rows of cups of one section and corresponding adjacent rows of adjacent sections for aligning and properly spacing the longitudinal and diagonal rows of cups of the sections.

9. A clip for securing together floor grid sections having aligned rows of material receiving cups, said clips comprising a sheet metal strip having a plurality of aligned tongues struck down from one side thereof and extending in the same direction longitudinally of the clip for engaging corresponding parts of adjacent sections and being of a width substantially equal to the width of the space between adjacent rows of cups.

In witness whereof I have signed my name at Milwaukee, Wisconsin, this 28th day of July, 1931.

EDWARD W. BURGESS.
